UNITED STATES PATENT OFFICE.

CHARLES H. LATOURELL, OF HEPPNER, OREGON.

GUN SIGHT.

Application filed July 22, 1924. Serial No. 727,508.

The present invention has relation to a sight, heat disseminator and anti-glare attachment for small fire-arms, such as a shot gun, whereby to insure a straight aim when 5 sighting a gun at an object with the chances in favor of making a hit.

The invention consists of a veiling rib which is flat and adapted to extend approximately the entire length of the gun barrel, 10 thereby insuring a straight line when taking aim with the chances favoring a hit.

Other objects and advantages will be apparent and suggest themselves as the nature of the invention is understood.

15 While the drawing illustrates an embodiment of the invention it is to be understood that in adapting the same to meet different conditions and requirements, various changes in the form, proportion and minor details of 20 construction may be resorted to without departing from the spirit of the invention.

Referring to the accompanying drawing forming a part of the application:

Figure 1 is a side view of a shot gun provided with a sight embodying the invention;

Figure 2 is an enlarged sectional view on the line 2—2 of Figure 1;

Figure 3 is an edge view of the sight;

Figure 4 is a top view of the gun sight 30 having an intermediate portion broken away;

Figure 5 is a plan view of a portion of the sight showing the same on a larger scale, and

Figure 6 is a sectional view on the line 35 6—6 of Figure 5.

Corresponding and like parts are referred to in the following description and designated in the several views of the drawing by like reference characters.

40 The gun 10 illustrated is typical of the type of fire-arms for which the device is designed and 11 denotes the barrel thereof which is provided at the muzzle with the usual sight 12 and in accordance with the present invention a pin 13 is provided at the breech for use jointly with the usual sight 12 as fastening means for a sight aiding attachment and shield 14 forming the

principal feature of the present invention and to be used in coaction with said sight 12. 50

The sight aiding attachment and shield 14 consist of a light flat body which when attached to the gun, that is, in operative position, extends along the top side of the barrel 11, being attached at its front end 55 to the attachment 12 and at its rear end to the pin 13. This sight is detachably connected to the elements 12 and 13 and for this purpose is provided at opposite ends with eyes 15. In the preferable construction a wire, strand, ribbon, or thin narrow strip of metal is bent back and forth upon itself to provide in effect a substantially imperforate flat strip which constitutes a narrow body protecting the eyes from the reflection of the sun on the barrel to insure an unobstructed straight line of vision when aiming the gun at an object and also serving as a disseminator for the heat of the barrel incidental to firing. The attachment 60 constructed in this manner is both light and flexible and adapted to be conveniently carried when detached from the gun. Moreover, it may be extended and maintained under tension when in position thereby assuring a straight bead.

65 The body 14 is arranged flatwise upon the barrel 11 and serves to dissipate heat and prevent light rays being reflected in such a manner as to blind or interfere with the 70 sighting of the gun. For this purpose the top side of the device is knurled or otherwise roughened as indicated most clearly in Figure 5.

75 What is claimed is:

A sight aiding attachment and glare shield for firearms comprising a flat strip consisting of a strand of metal bent back and forth upon itself and having its bends closely related, said strip being flexible and extensible for the purpose stated, and the terminals of said strip provided with means adapted to removably engage securing means on the top side of a gun. 80

85 In testimony whereof I affix my signature.

CHARLES H. LATOURELL.
